UNITED STATES PATENT OFFICE.

ROGER A. MCLEAN, OF WEST BAY CITY, MICHIGAN.

SPRING.

SPECIFICATION forming part of Letters Patent No. 252,686, dated January 24, 1882.

Application filed November 4, 1881. (No model.)

To all whom it may concern:

Be it known that I, ROGER A. MCLEAN, of West Bay City, in the county of Bay and State of Michigan, have invented a new and useful Improvement in Springs, of which the following is a full, clear, and exact description.

My invention consists of a box or well cast with vertical channels in which are loosely placed spring-metal strips arranged in pairs upon and across or at right angles to each other in such manner that the strips are free to move downward either at their ends or in the center in answer to the load, the whole being surmounted with a suitable follower attached to or separate from the load.

Reference is to be had to the accompanying drawings, forming a part of this specification, in which similar letters of reference indicate corresponding parts in both the figures.

Figure 1 is a plan view of my improved spring, the follower being removed; and Fig. 2 is a sectional elevation taken on the line *xx* of Fig. 1, the follower being also shown in section.

A represents the well or box, which is preferably of cast-iron, and formed with the corresponding channels *aa* and *bb* in the opposite walls, and with the corner enlargements or channels *d d*; and B represents the spring-metal strips, which in this instance are all of the same size and length. These strips are placed loosely in the channels of the well or box in pairs, alternately at right angles to each other, and are arranged so that the pairs of parallel strips rest alternately upon the ends and near the center of the strips, which are at right angles to them, as shown in the drawings.

Upon the pile of strips in the box or well is placed the follower D, which is provided with

a downwardly-projecting flange, *e*, and which completes the spring. Thus formed it will be seen that the spring will be durable, as the strips are required to bend but slightly, simple to make, owing to the strips being plain pieces of spring metal and all of the same form and length, easily and cheaply repaired, as it is necessary only to supply the place of the broken strips with new ones, and requiring no mechanical skill, and that the spring will not be wholly inoperative and worthless should one or more of the strips become broken, as is the case with springs of ordinary construction.

I am aware that it is not broadly new to arrange a series of plates at right angles to each other in a box, with the ends of one set resting in vertical grooves in the sides of the box; and I am also aware that a box for containing a series of flat spring-plates has been provided with corner enlargements to receive blocks upon which the said plates rest, and I therefore do not claim such; but

What I do claim, and desire to secure by Letters Patent, is—

The combination, with the strips B, of a uniform size, arranged in pairs, alternately at right angles to each other, and having the parallel pairs resting alternately upon the ends and near the center of the pairs of the box A, provided with the channels or grooves *aa* and *bb* in its inner walls to receive the ends of the inner plates, and the corner enlargements or channels *d* to receive the ends of both sets of outer plates, substantially as and for the purpose set forth.

ROGER A. MCLEAN.
